UNITED STATES PATENT OFFICE

130,153

DESIGN FOR A PIPE BOWL CLEANER

Orlando Z. McCoy, Cleveland, Ohio

Application April 24, 1939, Serial No. 84,513

Term of patent 7 years

To all whom it may concern:

Be it known that I, Orlando Z. McCoy, a citizen of the United States of America, residing at Cleveland, in the county of Cuyahoga and State of Ohio, have invented a new, original, and ornamental Design for a Pipe Bowl Cleaner, of which the following is a specification, reference being had to the accompanying drawing, forming a part thereof, in which:

Fig. 1 is a top plan view of the concave face of the pipe bowl cleaner, showing my new design;

Fig. 2 is a plan view of the opposite or convex face thereof.

Fig. 3 is a side elevational view showing one lateral edge of the cleaner.

Fig. 4 is a side elevational view, showing the edge opposite to that shown in Fig. 3, and

Fig. 5 is an end elevational view of the tip end thereof.

I claim:

The ornamental design for a pipe bowl cleaner, substantially as shown.

ORLANDO Z. McCOY,
